UNITED STATES PATENT OFFICE.

PETER JACOBI, OF BAD MANHEIM, GERMANY.

SIGNALING APPARATUS.

SPECIFICATION forming part of Letters Patent No. 726,933, dated May 5, 1903.

Application filed July 21, 1902. Serial No. 116,444. (No model.)

To all whom it may concern:

Be it known that I, PETER JACOBI, a subject of the German Emperor, residing at Bad Manheim, in the Empire of Germany, have invented certain new and useful Improvements in Signaling Apparatus, of which the following is a specification.

The present invention is devised to prevent railway collisions, and is equally applicable in whatever way the trains approach one another and whether the locomotive is traveling backward or forward.

The principal feature of the invention consists in novel mechanism whereby gongs upon the locomotive are sounded in such a way that the number of strokes indicate various signals—such as "stop," or "way clear," and the like—said mechanism being controllable by and with the ordinary visual signaling apparatus.

In the accompanying drawings, Figure 1 is a side view, and Fig. 2 a face view, of the gong-striking devices. Fig. 3 is a side view of the lever system, the levers being in upper right position. Fig. 4 is a front view of the same, and Fig. 5 shows a system of six levers.

On both sides of the locomotive-cab and the guard's van are arranged gongs in a suitable position at the height of the ear. In place of the clapper is a stiff metal spring *i*, one end of which is coiled around a bolt *h* and is attached thereto, while the other end carries a pin *l*. The gongs can be connected together by cross-rods below their lever ends or in some such manner. The upright portion of the spring *i* rests against two pins *m* and *m'* of a two-armed lever *o*, pivoted at *n*, which lever carries at its lower end a horizontal cross-piece *p*. By reason of the lever *o* being provided with the two pins *m* and *m'* on both sides of the fulcrum *n* the lever can be rocked either to the right or to the left, (see Fig. 1,) and each time, owing to the resiliency of the spring *i*, the gong *k* would be sounded. This is especially important for the gongs on the locomotive, which changes its position on the train and can go either forward or backward.

The gong-signal-actuating apparatus comprises a series of levers which are placed in the case of a single track on one of the outer sides of the rails, and in the case of a double

track on the outer side of the right-hand rail. To prevent one train colliding with another from behind, the following is the arrangement employed:

From one sleeper to, perhaps, the neighboring one stretches an angle-iron *a*, which is screwed to both sleepers, so that its side which is toward the outside of the rail *b* is distant therefrom about six centimeters. This angle-iron *a* forms a bracket for a lever system *A*, consisting of three levers, the first of which, *c*, has an additional arm *c'* upon its upper arm, while the other two, *d d*, are two-armed in the ordinary sense of the word. All three can simultaneously be turned upon the pivots *e* in the bracket *a* if the wire which connects their lower ends is pulled. This lever arrangement is placed at a short distance in front of an advance, principal, block, and starting signal, which are connected with the apparatus for actuating the switches.

When a locomotive passes, with its train, over the system *A*, should the usual signal not be seen or should it be passed unnoticed on account of mist or fog then the attendants on the locomotive will be informed of the condition of the section in the following manner: If the section is occupied, all the three levers *c d d* are vertical, and the gongs will therefore be three times sounded, which signifies "stop." This signal will be heard by the drivers and stoker. If, on the other hand, the section is clear, the levers will be depressed by pulling the wire *f*, which is of course in connection with the signaling apparatus, so that the levers will assume the dotted position of Fig. 3. In this case the finger *c'* of the fork-lever *c* takes a vertical position, and the gongs of the advancing train are therefore sounded once, which signifies "clear way." If the train gets the signal "stop," it advances slowly as far as the principal or block signal, where a lever *r*, such as is used for altering the points, is thrown over under the control of the driver, which independently of any further signaling apparatus actuates a draw-wire *q*, which works a system *B* of six levers of the same form as the levers *d* in the system *A* at a distance of five hundred to one thousand meters away, so that they move from the oblique to the vertical position. The drawing apparatus consists of an endless

wire which runs over rollers *g* and in one place is provided with a connection for the under arms of the six levers. It is also possible to actuate the system B by means of the 5 wire *g* independently of the lever *r* every hundred meters or so. If, however, the levers of the system are vertical, the train following the one which is stopped receives six strokes of the gong, which signifies "great 10 danger" ahead, so that in any case the driver will not dare to go farther than the signal in front or slowly up to the stopped train. This arrangement is of especial value if the first 15 train is stopped owing to a defect in its engine or the like and is compelled to remain on the track, and this cannot be intimated to the station through which the following train runs in the same direction. Such an accident renders necessary the blocking of the 20 whole section with apparatus of the last-described kind B, which are, however, all independent of one another.

For the second instance, the prevention of the collision of the two trains approaching 25 one another, the arrangement is as follows: The lever arrangement is connected with the starting-signal at the station by means of a wire rope, the tension of which can be adjusted, and the wire rope runs over rollers 30 at a distance of a few centimeters above the level of the ground or where there is traffic across the road in a tube below the surface of the ground (also the whole wire rope can be put under ground) around about the entry and exit lines of a terminus. The arrangement of wire rope is naturally doubled at stations through which the train runs. So long as no train enters or leaves the station the levers remain down. If, however, a 35 train leaves, then simultaneously with the starting-signal the levers (which in this case are formed without the fork *c*) on all the tracks which lead onto the track of the outgoing train are raised into the vertical position 40 from the signal-box by means of the wire rope, while on the principal track the lever system A, which has the fork and which is naturally in connection with the starting-signal, is correspondingly set. When shunting, if one train should be running into another on its side the train which is being shunted receives the signal "stop" by a triple stroke upon the gong, which is heard as soon 45 as the outgoing train leaves the station. Good care must also be taken in the station that a train only enters upon that track upon 50 which it must travel.

The means for actuating the levers are the same as usual.

60 What I claim, and desire to secure by Letters Patent of the United States, is—

1. In a railway-train signaling apparatus, the combination of a connected adjustable series of parallel contact-levers beside the 65 track, a lever upon the train adapted to successively engage the contact-levers when the

latter are in a vertical position, and audible mechanism on the train actuated by said train-lever.

2. In an apparatus for preventing collisions 70 on railways, the combination of a vibrating lever on the train or engine, having one end depending near the track, a spring beside the upper end of said lever adapted to be vibrated thereby, and a gong adapted to be sounded by said spring; with a series of parallel adjustable contact-levers beside the track adapted in one position to successively engage the lower end of said vibrating lever as it moves therepast.

80 3. The combination of a gong, a spring-hammer therefor, and a two-armed lever actuating the spring-hammer; with two pins upon said lever, one above and one below the pivot thereof and directly bearing upon the spring-hammer and adapted to vibrate the hammer when the lever is oscillated, substantially as described.

4. In an apparatus for preventing collisions 90 on railways, the combination of a vibrating lever on the train or engine, having one end depending near the track, a spring beside the upper end of said lever, a hammer on said spring and a gong adapted to be sounded by said hammer when the spring is vibrated; 95 with a series of parallel adjustable levers beside the track adapted to successively engage and actuate the train-lever as it moves therepast.

100 5. In an apparatus for preventing collisions on railways the combination of a gong, and an actuating-lever therefor arranged on the train, so that the number of strokes on the gong indicates the condition of the section of the line; with a plurality of adjustable two-105 armed levers, pivoted beside the rail, and a connection between the lower arms of said levers whereby they may be brought to a vertical or oblique position, the upper arms of said levers successively engaging the actuating-lever when the former are in a vertical position, substantially as described.

110 6. In an apparatus for preventing collisions on railways, the combination of a vibrating lever, on the train or engine, having one end 115 depending near the track, a spring beside the upper end of said lever and a gong adapted to be sounded by said spring; with a series of adjustable levers beside the track adapted to engage and actuate the train-lever as it 120 moves therepast, one of said levers being forked so that when the series of levers are depressed one fork of said lever remains in position to engage the moving lever and sound the gong.

125 In testimony whereof I have hereunto set my hand in the presence of two witnesses.

PETER JACOBI.

Witnesses:

BERNHARD KAISER,
JEAN GRUND.

It is hereby certified that the residence of the patentee in Letters Patent No. 726,933, granted May 5, 1903, upon the application of Peter Jacobi, for an improvement in "Signaling Apparatus," was erroneously written and printed "Bad Manheim, Germany," whereas said residence should have been written and printed *Bad Nauheim, Germany*; and that the said Letters Patent should be read with this correction therein that the same may conform to the record of the case in the Patent Office.

Signed and sealed this 28th day of July, A. D., 1903.

[SEAL.]

E. B. MOORE,

Acting Commissioner of Patents.
